KILN LINING

Harry S. Lee, Detroit, Mich.

Application March 24, 1932. Serial No. 600,945

8 Claims. (Cl. 222—7)

My invention relates to cement kilns and has particular reference to an improved heat insulating lining therefor.

An object of the invention is to secure greater efficiency in cement kiln operation by more effectively and completely insulating the interior of the kiln in which the material is burned from the exterior shell. In this way the losses through radiation of the heat transferred to the kiln shell are substantially reduced and of necessity the consumption of fuel per unit of finished product from the kiln is decreased.

More particularly, an object of the invention is to provide a lining built up of fire bricks so molded that the major portion of the interior of the kiln shell may be lined with some conventional type of insulating material such as "kiesel-guhr" or "diatomaceous earth". Hitherto it has been customary to provide a ring of solid fire brick lining at each end of the kiln of a width varying from four to eight feet and then lining approximately the same length of kiln with insulating material over which fire brick blocks, of less depth than that of which the end rings are composed, are positioned. The portions of the kiln length thus insulated were alternated with rings substantially like the end rings for the purpose of retaining the assembly properly positioned and the interior of the kiln so lined was, of course, flush throughout its length. However, so lining the kiln provided but a relatively small area, insulated other than with the fire brick, because of the fact that but a relatively small length of kiln shell could be lined continuously therein without the interpositioning of a ring of plain fire bricks. This limitation to the insulated area resulted from inability to firmly position the blocks which were laid over the insulating material placed next to the kiln shell by any means other than the alternating rings of full depth bricks which were securely positioned by cement to the kiln shell itself.

My invention contemplates the provision of individual blocks each including what may be regarded as a "foot" portion adapted to contact the interior of the kiln shell and a spaced portion for the retention of insulating material between the block and the kiln. The contacting foot portion or feet portion in some modified structures, is relatively small and the major portion of that face of the brick adapted to lie directly adjacent the kiln shell is spaced from the said shell, thereby permitting insulation of the major portion of each brick from said shell. These bricks are so constructed that the por-

tions held in spaced relation to the shell are in alignment along the length of the kiln, and in some instances around the circumference also.

This is particularly desirable in view of the fact that another object of my invention is the provision of an entirely novel means of positioning the insulating material between the bricks and the shell, to wit, the pumping thereof into the contiguous passages described above.

Various other meritorious features of the invention will be apparent from the following description taken in conjunction with the drawings wherein like numerals refer to like parts throughout the several figures and wherein:

Fig. 1 is an end elevation of the kiln.

70

Fig. 2 is a side elevation of the kiln partly broken away and in section,

Fig. 3 is an enlarged elevation similar to Fig. 1, partly broken away and in section,

Fig. 4 is a detail of one type of improved lining 75 block,

Fig. 5 illustrates a block through which insulating material may be injected.

Fig. 6 is a modified form of the block illustrated in Fig. 5,

80

Fig. 7 is a longitudinal section illustrating the use of the block shown in Fig. 6,

Fig. 8 is an elevation, partly in section, of the assembly shown in section in Fig. 7,

Fig. 9 illustrates the modified form of block 85 shown in Fig. 8,

Fig. 10 is another modified form of block.

Fig. 11 is an elevation partly in section illustrating the use of the block illustrated in Fig. 12,

Fig. 12 illustrates another modified form of 90 block.

Fig. 13 is a longitudinal section of the assembly shown in Fig. 11.

Referring now to the drawings, the numeral 10 indicates the shell of the kiln. Figs. 1-5 disclose 95 a single form of lining which is comprised of adjacent rings formed of blocks 12 similar to that illustrated in Fig. 4. It will be noted that each of these blocks includes a foot portion 14 which is adapted to seat upon the interior of the kiln 100 shell 10 and a cut away portion 16. The sides of the block are each provided with stepped portions 18 and 20 which assist in positioning the blocks when laid. In each ring one block 22 of the type illustrated in Fig. 5 is included. This 105 block includes the stepped portions 18 and 20 but in lieu of the cut away portion 16 there is an aperture 24 extending from the inner face of the block through the major depth thereof and opening on the side of the block at a point positioned 110

in the same location as is the cut away portion 16 of the blocks 12.

As indicated in Fig. 2, the blocks 22 are circumferentially offset a distance of one block in 5 each succeeding ring.

In the formation of the lining the blocks are all laid as indicated and insulating material of any desirable type such as the diatomaceous earth above mentioned is pumped into the apertures 24.

10 Inasmuch as a block 22 is positioned along each axial row of lining bricks at regular intervals the insulating material pumped into each of the apertures 24 will be forced down into the passageway adjacent the kiln shell 10 and therealong until it reaches the dead end provided by the next 15 ensuing block 22. Inasmuch as the force with which the insulating material may be pumped through the opening 24 is limited it has been found advisable to utilize one block 22 of the type 20 illustrated in Fig. 2 about every ten axially aligned blocks.

It will thus be apparent that approximately 75% of the kiln shell is lined with insulating material, inasmuch as this approximate percentage 25 of the outer surface of each block is provided with the cut away portion 16 into which the insulating material is pumped. Furthermore, each of the blocks 12 is provided with a foot portion which serves to more firmly position it in its proper 30 place and there is no necessity for utilizing alternating rings of solid blocks adhering to the interior surface of the shell to position the other blocks which overlie the insulating material. Each block is positioned and each block is insulated. 35

In order to insure the complete filling of the passageways provided by the cut away portions of the lining bricks, it has been found advantageous to pump the insulating material in at one 40 end while applying suction to the other end of the passage.

Certain modified forms of blocks analogous to block 12 shown in Fig. 4 have also been found to possess certain advantages. These features are 45 illustrated on sheet 2 of the drawings wherein two modified forms of blocks 26 and 28 have been illustrated in Figs. 9 and 12 respectively. The block 26 includes a pair of oppositely disposed feet 29 and 30 adapted to seat against the interior 50 surface of the kiln shell, the cut away portion therebetween providing an arched passageway 32 adapted to receive the insulating material.

Block 28 is provided with four legs 35 adapted to seat upon the interior of the kiln shell and 55 it will be apparent that these blocks when laid provide passageways 34 and 36 extending in right angled directions. The form illustrated in Fig. 12, block 28, provides a maximum space 60 adapted to receive insulating material and it will be apparent that such material will spread over almost the entire interior surface of the kiln shell when injected from all of the available injection points.

Fig. 6 illustrates a block 38 adapted for use 65 in conjunction with block 12 and is a substitute for block 22 when it is desired to suck the insulating material from one end of the passageway while pumping it through the other. The oppositely directed passageways 40 and 42, each opening 70 radially into the assembled lining, permit this operation.

Block 44 illustrated in Fig. 10 is utilized in conjunction with blocks 26 or 28 and permits both pumping and sucking simultaneously. In 75 all instances it will be noted that the injection

blocks constitute dead ends which limit the flow of the insulating material during the pumping and sucking operation. Fig. 11 illustrates an assembly utilizing blocks 28 in conjunction with blocks 44 while Fig. 8 illustrates an assembly utilizing blocks 26 in combination with the same injection and dead end block 44.

While I have illustrated certain preferred forms and described certain preferred methods of securing this improved insulation of the kiln shell from the interior thereof, it is believed that the broad idea of providing individual blocks each having a foot portion to assist in positioning it within the kiln shell and forming a passageway adapted to receive insulating material injected from the interior of the kiln is novel and for that reason the invention is to be limited only by the scope of the appended claims.

By reason of the fact that the foot portion of each brick is in contact with the shell of the kiln sufficient heat passes through the brick and to the shell to prevent the temperature of the brick becoming so great that rapid deterioration thereof results. In fact this heat "bye-pass" through each brick, so to speak, lengthens the 100 useful life of the lining brick materially over that of the brick spaced from the kiln shell by insulating material.

What I claim is:

1. A lining block including an interior passageway extending from one end of said block along the major portion of its depth and opening through the side face of said block adjacent the opposite end thereof. 105

2. A lining block having arcuate end faces and a passageway extending from one arcuate end face through the block and terminating at one side adjacent the opposite arcuate faced end. 110

3. A kiln block including a pair of interior passages extending from one end of said block 115 along the major portion of its depth and opening in opposite directions into the respective side faces of said block adjacent the opposite end thereof.

4. A kiln lining comprising a plurality of series of lining blocks, each block having a portion contacting the surface lined and provided with contiguous cut away portions forming a passage between the major portion of the block and the surface lined, and a dead block at each 120 extremity of each of said passage forming series, each dead block including an opening in the interior face of the block communicating with the passage formed between the blocks and the 125 surface lined. 130

5. In a kiln, an outer shell, a liner of heat resisting blocks arranged in successive tiers over said shell, each tier provided with a plurality of independent groups of adjacent blocks similarly undercut adjacent to the shell providing a space 135 extending along said tier underneath each group of blocks, said groups of blocks separated from each other by partition blocks located at spaced intervals in the tier, and a passageway extending through each partition block from its outer 140 surface to the space adjacent said undercut blocks.

6. In a kiln, an outer shell, a liner of blocks arranged in successive tiers over the surface of the shell, certain adjacent blocks in each tier 145 being undercut providing a space between the said blocks and the shell, a partition block in each tier separating adjacent groups of undercut blocks and the spaces there underneath from each other, and passageways through the par- 150

- tion blocks leading from said spaces to the outer surface of the blocks.
7. A kiln liner formed of blocks, certain of said blocks being undercut and certain other blocks having passageways extending from one end of the blocks to a point adjacent to the opposite end, and an opening through one side of the blocks into the space underneath the undercut blocks. 80
- 10 8. A kiln liner formed of blocks, spaced apart groups of adjacent blocks being undercut providing a continuous space extending underneath an adjacent group of blocks. 85
